UNITED STATES PATENT OFFICE.

HIRAM D. JEWETT AND ISRAEL D. JEWETT, OF ST. OMER, INDIANA.

IMPROVEMENT IN MEDICAL COMPOUNDS.

Specification forming part of Letters Patent No. 127,060, dated May 21, 1872.

Specification describing a certain medical compound, called Good Samaritan Oil, invented by HIRAM D. JEWETT and ISRAEL D. JEWETT, of St. Omer, in the county of Decatur and State of Indiana.

In preparing this oil we use the following-named ingredients, and substantially in the proportions named: One ounce of oil of oragnum; one ounce of oil of hemlock; one ounce of oil of cedar; one ounce of oil of sassafras; one ounce of oil of winter-green; two ounces of oil of olives; two ounces of tincture of myrrh; two ounces of oil of valerian; two ounces of tincture of capsicum; two ounces of aqua ammonia; one-half ounce gum camphor; one ounce of laudanum; one ounce of sulphuric ether; one quart of alcohol. All of the above-named oils and the gums are to be cut with the best of alcohol, after which the tinctures are to be added, and the whole thoroughly agitated and mixed together, when it is ready for use.

This compound we regard as a specific for many diseases, such as diphteria, croup, burns, rheumatism, neuralgia, relaxation of the bowels, and various other complaints. It may also be used for the cure of the following-named diseases of animals: Colic, botts, poll-evil, sprains,

ring-bone, and various other diseases and injuries to which they are subject.

In applying this oil for all that class of diseases where it is used externally, it should be done by bathing the parts affected twice each day, and in bad cases three or four times each day. When used internally, it may be dropped upon a spoonful of sugar, or it may be taken in any other convenient manner, a dose consisting of from five to thirty drops, according to the age and condition of the patient.

What we claim as our invention, and desire to secure by Letters Patent, is—

The manufacture or preparation of a compound which is denominated "Good Samaritan Oil," of the ingredients named, and in substantially the quantities specified, it being for the purpose set forth.

In testimony whereof we have signed our names to this specification in the presence of two subscribing witnesses.

HIRAM D. JEWETT.
ISRAEL D. JEWETT.
